CLAIM

The ornamental design for a projectile, as shown and described.

DESCRIPTION

FIG. 1 is a top, front, right-side perspective view of a projectile according to an aspect of this disclosure;

FIG. 2 is a bottom, rear, left-side perspective view thereof; FIG. 3 is a top view thereof, a bottom view thereof being symmetrical to the top view;

FIG. 4 is a right-side view thereof, a left-side view thereof being symmetrical to the right-side view;

FIG. 5 is a front view thereof;

FIG. 6 is a rear view thereof;

FIG. 7 is a top, front, right-side perspective view of a projectile according to an additional aspect of this disclosure;

FIG. 8 is a bottom, rear, left-side perspective view thereof; FIG. 9 is a top view thereof, a bottom view thereof being symmetrical to the top view;

FIG. 10 is a right-side view thereof, a left-side view thereof being symmetrical to the right-side view;

FIG. 11 is a front view thereof; and,

FIG. 12 is a rear view thereof.

The broken lines depict portions of the projectile that form no part of the claimed design.

1 Claim, 12 Drawing Sheets
